UNITED STATES PATENT OFFICE.

JOHN ROWE, OF CASEY, IOWA.

DESIGN FOR A MUD-LUG.

54,563.

Specification for Design.

Patented Mar. 2, 1920.

Application filed June 2, 1919. Serial No. 301,356. Term of patent 14 years.

To all whom it may concern:

Be it known that I, JOHN ROWE, a citizen of the United States of America, and resident of Casey, Guthrie county, Iowa, have invented a new, original, and ornamental Design for a Mud-Lug, of which the following is a specification when taken in connection with the accompanying drawing.

Figure 1 is a plan view and Fig. 2 a side elevation of a mud lug embodying my design.

I claim as my invention—

The ornamental design for a mud lug as shown.

JOHN ROWE.
